US00D873427S

(12) **United States Design Patent** (10) **Patent No.:** **US D873,427 S**
(45) **Date of Patent:** **** Jan. 21, 2020**

(54) **FEEDING DEVICE**

(71) Applicants: **Jessica Murphy**, Hastings on Hudson, NY (US); **Satya Celeste Stainton**, Brooklyn, NY (US)

(72) Inventors: **Jessica Murphy**, Hastings on Hudson, NY (US); **Satya Celeste Stainton**, Brooklyn, NY (US)

(73) Assignee: **BebeBoost LLC**, Hastings-on-Hudson, NY (US)

(**) Term: **15 Years**

(21) Appl. No.: **29/627,038**

(22) Filed: **Nov. 22, 2017**

(51) LOC (12) Cl. **07-01**

(52) U.S. Cl.

USPC **D24/199**; D9/455

(58) **Field of Classification Search**

USPC D24/199; D30/133; D19/75; D9/455;
D7/397, 619.1

See application file for complete search history.

(57) **CLAIM**

The ornamental design of a feeding device, as shown and described.

DESCRIPTION

FIG. 1 is a top, front, right side perspective view for a feeding device, showing my new design;

FIG. 2 is a front view thereof;

FIG. 3 is a right side view thereof; and,

FIG. 4 is a top view thereof.

The broken lines shown in the drawings depict portions of the article and form no part of the claimed design.

1 Claim, 4 Drawing Sheets
